UNITED STATES PATENT OFFICE

RALPH R. VAN DUSEN AND RAY A. PHILLIPS, OF WICHITA, KANSAS

DESIGN FOR A REFRESHMENT BOOTH

Application filed June 24, 1930. Serial No. 36,160. Term of patent 3½ years.

To all whom it may concern:

Be it known that RALPH R. VAN DUSEN and RAY A. PHILLIPS, citizens of the United States of America, residing at Wichita, in the county of Sedgwick and State of Kansas, have invented a new, original, and ornamental Design for a Refreshment Booth, of which the following is a specification, reference being had to the accompanying drawings, forming a part thereof.

Fig. 1 is a front view of the refreshment booth. Fig. 2 is a view of the right side of

the refreshment booth. Fig. 3 is a rear view of the refreshment booth. Fig. 4 is a view of the left side of the refreshment booth. Fig. 5 is a view looking down on top of the refreshment booth.

We claim:

The ornamental design for a refreshment booth, as shown.

In testimony whereof we affix our signatures.

RALPH R. VAN DUSEN.
RAY A. PHILLIPS.
